In Sweden July 23, 1945

3 Claims. (Cl. 20—0.5)

1

This invention relates to a panel construction and the like and more particularly to a double walled panel having supporting means intermediate the spaced walls.

The invention is particularly applicable to doors, partitions and the like, but it will be understood that it is not limited thereto but may be embodied with advantage in wall construction in general.

In wall constructions for which the invention is intended, it is important that the panel sheets remain plane and smooth and that they do not bend or warp under atmospheric conditions. To this end, supporting members have been interposed between the spaced walls in order to provide supports for and prevent warping of the panel sheets. The spaced walls which may consist of wood, plywood, wallboard or the like, are usually applied to the sides of a frame of wood or other material which will provide proper attachment and support for the panel sheets.

Heretofore, these intermediate supports have usually been in the nature of ribs arranged in lattice-like formation or of spaced members of wood which are glued to the interior surfaces of the side panels.

These conventional constructions, however, have shown a tendency to cause unsightly deformations of the panel sheets. The deformations might be partly avoided by gluing greater portions of the panel sheets to the filler material, but this method requires too much glue. It has also been proposed to use relatively soft material as filler between the walls in order to avoid such deformations, but this construction does not render the bond between the panel sheets sufficiently rigid to counteract the tendency of the panel sheets to warp or bend.

It is therefore among the objects of the present invention to provide a double walled panel construction which has a supporting structure between the walls which possesses sufficient rigidity to provide a firm bond between the walls and still afford elasticity sufficient to prevent deformation of the panel sheets at the points of attachment between the spaced panels and the intermediate supporting structure.

Additional objects and advantages inherent in the invention will become more apparent from the following specification taken in conjunction with the accompanying drawings which disclose by way of example a preferred and a modified embodiment of the inventive concept.

In the drawing:

Figure 1 is a longitudinal section of a door em-

2

bodying the invention showing its adjustment to a door frame which has been partially shown in broken lines.

Figure 2 is a fragmentary front elevation showing a portion of one of the side panels broken away.

Figure 3 is a longitudinal section similar to Figure 1 showing a modification, and

Figure 4 is a fragmentary front elevation similar to Figure 2 showing the modification illustrated in Figure 3.

The aforesaid may be obtained by combining a relatively hard material with a relatively soft material in the intermediate supporting structure.

More specifically the invention contemplates a wall construction comprising a pair of spaced panels, which panels are applied to opposite sides of a frame, and between which panels is arranged an intermediate supporting structure consisting of a series of ribs of relatively hard and rigid material, which ribs are free of direct contact with the panels and are provided on either one or on both sides with a relatively soft material which projects beyond the ribs so as to contact the panels and exert a slight pressure thereagainst.

Referring in greater detail to the drawing, in which the same reference characters serve to indicate the same or analogous parts, the panels 10, which may consist of plywood, fiber, wood, wallboard, plastic or other suitable material, are connected to the frame 11, which may consist of wood, deadwood or some other suitable material. In the particular embodiments shown in the drawing, the frame is recessed at opposite sides to engage the frame 12 of the door opening which has been shown in broken lines since it does not form part of the invention. One side of the door may be hinged to the frame 12 as at 13.

Between the panels 10 are arranged a series of spaced ribs 14 of relatively hard and rigid material, such as hard wallboard, plywood, hard fiber, wood, etc. These ribs preferably extend from one side of the frame to the other. In the embodiment shown in Figure 1, these ribs are arranged with their wider sides parallel to the panels 10.

To the ribs 14 are attached members 15 of relatively soft material, such as porous wallboard, and which members are of such thickness that they are subjected to a slight pressure by the panels 10 when the latter are adjusted to the frame 11.

The members 15 may be covered with glue or similar material prior to the assembling process and in this manner they will become glued to the interior surfaces of the panels when the latter are pressed on to the frame 11.

The modification shown in Figures 3 and 4 differs from the embodiment shown in Figures 1 and 2 in that the ribs 14 are arranged with their wider sides perpendicular to the panels 10. It is important, however, that the edges 16 of these ribs are free of direct contact with the interior surfaces of the panels. On the other hand, the members 15 have been selected of such width or height that they exert a slight pressure against the interior surfaces of the panels when the latter are adjusted to the frame 11.

In the embodiments shown in the drawing, the members 15 have been shown as individual pieces attached to the ribs 14 in spaced relationship from one another and the pieces on adjoining ribs arranged in alternate fashion. It should be understood, however, that various other arrangements may be made without departing from the invention. Furthermore, instead of consisting of individual pieces, the members 15 may consist of a continuous strip, but in this case it might be desirable to recess the strips at intervals in order to provide a plurality of supporting points instead of one continuous supporting line.

In order to obtain suitable compression of the softer material comprising the members 15, it has been found advantageous to make the members 14 about 2% larger than the size they will have when glued to the panels.

It will be understood that by reason of the relatively soft or compressible members 15 which are fixed to the relatively stiff or non-compressible ribs 14 and exert a slight pressure against the interior surfaces of the panels 10, a firm and still resilient bond is provided between the panels which is free of the objections connected with a supporting structure composed entirely of either rigid or soft material.

It should also be emphasized that this description has been given by way of example and not by way of limitation. On the other hand, the invention lends itself to a variety of expressions within the scope of the following claims.

What is claimed is:

1. A double walled panel construction comprising a pair of spaced panels, a series of relatively spaced and comparatively thin ribs of substantially rigid material extending between said panels and being spaced from the interior surfaces of said panels, and a series of comparatively thick members of resilient material spaced along each of said ribs and engaging the interior surfaces 10 of said panels in pressure-urged relationship.

2. A double walled panel construction comprising a frame, a pair of spaced panels, a series of relatively spaced and comparatively thin ribs of substantially rigid material extending between 15 said panels and connected to opposite frame members, said ribs being spaced from the interior surfaces of said panels, and a series of comparatively thick members of resilient material spaced along each of said ribs and engaging the interior surfaces 20 of said panels in pressure-urged relationship.

3. A double walled panel construction comprising a pair of spaced panels, a series of relatively spaced and comparatively thin ribs of substantially rigid material extending between said panels and being spaced from the interior surfaces of said panels, and a series of comparatively thick members of resilient material spaced along each of said ribs and engaging the interior surfaces 25 of said panels in pressure-urged relationship, said members being spaced along said ribs in alternating relationship to the members on the adjoining rib so that said members on one rib will be located in the spaces between the members on 30 the adjoining rib.
